UNITED STATES PATENT OFFICE

162,973

EXPANSIBLE BRACELET OR THE LIKE

Samuel Meyerson, Brooklyn, N. Y.

Application December 14, 1950, Serial No. 13,435

Term of patent 14 years

(Cl. D45—4)

To all whom it may concern:

Be it known that I, Samuel Meyerson, a citizen of the United States, residing in Brooklyn, county of Kings, State of New York, have invented a new, original, and ornamental Design for an Expansible Bracelet or the like, of which the following is a specification, reference being had to the accompanying drawing, forming part thereof, in which

Figure 1 is a top plan view of an expansible bracelet embodying the new design,

Figure 2 is a side elevational view of the bracelet,

Figure 3 is a top plan view thereof with the links in expanded position.

Figure 4 is an enlarged perspective view of one of the top links,

Figure 5 is a sectional view taken on line 5—5 of Fig. 4.

The dominant feature of my design resides in the top link elements shown in full lines, the bottom links being conventional as indicated by the broken line disclosure thereof and a portion of the center of the bracelet being broken away for convenience of illustration only as shown by the dotted lines across the center of the bracelet in Figs. 1, 2 and 3.

I claim:

The ornamental design for an expansible bracelet or the like, as shown and described.

SAMUEL MEYERSON.
